CAR UNDERFRAME

John E. Muhrfeld, Scarsdale, N. Y.

Application March 18, 1932, Serial No. 599,610

12 Claims. (Cl. 105—256)

The invention relates to railway rolling stock and consists in a novel arrangement of hopper doors and underframe structure particularly adapted for cars which can be used either as a general utility gondola car or a side dump or hopper bottom type of car although some features of the invention are not limited to such cars.

Heretofore, side dump hopper cars have been provided with wide internal bracing for the sides of the car and with deep hoppers and therefore they could not be used for carrying long articles such as pipe, etc. and the deep hoppers would not permit a man, without difficulty, to work inside of the car for handling such articles. They have also been provided with doors which are pivoted to the sides of the car above the discharge opening and which do not support material while it is being discharged. These cars included an inclined floor extending outwardly beyond the rails on each side so as to discharge the material on the outside of the rails. They have also included center sills and side sills, either or both of which serve as the main longitudinal members of the underframe for carrying the car load and transmitting buffing and pulling forces and, where inclined floor structure was provided between the center sill and the side sill, the floor structure has been superimposed upon the complete structural members of the underframe and has contributed nothing to the rigidity and strength of the underframe.

One of the main objects of the present invention is to provide a side dumping car having an inclined floor between the trucks, and doors which are hinged to the outer portions of floor to form an extension of the floor for discharging material on the outside of the rails when the doors are in open position.

Another main object of the present invention is to provide a side dumping car having an inclined floor over the trucks, and doors which are hinged to the upper portions of the underframe and which doors do not form any substantial extension of the floor, for discharging material on the outside of the rails when the doors are in open position.

Another main object of the invention is to provide an underframe for a car of the type referred to in which the inclined floor portions form a substantial contribution to the underframe structure and at the same time provide a floor having a minimum width and weight and the necessary strength.

Another object of the invention is to provide hoppers which will be shallow enough to permit

a man to move from one part of the car to another without much difficulty when it is used as a general utility car.

It is another object of the present invention to provide a floor inclined downwardly and outwardly from the center sill substantially throughout the length of the car so that the entire load may be discharged through downwardly and outwardly opening doors.

Another object of the invention is to eliminate to a substantial degree the deterioration of the car structure due to the loosening up of joints between interconnected parts and due to the corrosion resulting from the seepage of dirt and moisture into the crevices between interconnected parts.

These and other detail objects of the invention are attained in the structure illustrated in the accompanying drawings in which—

Figure 1 is a top view of one-half of the car underframe.

Figure 2 is a side elevation of the same.

Figure 3 is a vertical longitudinal section taken on the line 3—3 of Figure 1.

Figure 4 is an end view of the underframe.

Figures 5, 6, and 7 are vertical transverse sections taken on the corresponding section lines of Figure 1.

Figure 8 is a detail section of a part of a cross beam and is taken on the line 8—8 of Figure 7.

The car superstructure side plates A and corresponding end plates (not shown) are mounted on the underframe B. The underframe comprises a center sill structure having spaced vertical webs 1 extending throughout the length of the car and having reinforcing flanges 2 along their lower edges. Side sills 3 extend from end to end of the car and are at a higher level over the car trucks indicated by the wheels 4, than they are intermediate the trucks. The underframe has a number of transverse members including end sills 5, preferably of box-shape cross section, bolsters 6 also of box-shape or inverted U-section, and a plurality of cross beams 7, each comprising a vertical web having upper flanges 7a and diverging lower flanges 7b.

A floor which forms the bottom inclined walls of the hoppers extends downwardly and outwardly from the longitudinal center line of the underframe towards the side sills and merges with the center sill webs 1 as indicated at 8. Between the trucks, this floor includes sections 9 with their lower edges terminating approximately midway between the center sill webs 1 and side sills 3 at points above and a short distance inside of rails 5.

as indicated by relative positions of wheel flanges in Figure 7. Over the trucks, the floor sections 10 extend downwardly and outwardly from the center line of the car at a less steep angle and 5 also extend outwardly a greater distance than sections 9 to points substantially directly beneath the side sills 3. Figure 5 shows the relative positions of the inclined floor sections 10 and the truck wheels 4 and wheel pieces 18. Each end of 10 each floor section merges with the edges of the cross beam web 7 or its flanges 1b or with the corresponding elements of the bolster or center sill.

Preferably all of the elements of the under- 15 frame described above including the hopper floor sections and side sills are part of an integral cast structure whereby the usual overlapping flanges, rivets and assembling works are eliminated and there are no crevices between portions of the 20 floor and the cross beams and center sills and side sills, etc. to interrupt the flow of material or to accumulate dirt and moisture or to loosen up and affect the operation of the doors and door mechanism applied to the underframe.

25 Floor sections 9 include hinge butts 11 for mounting doors D which swing upwardly with their outer edges in contact with the depending flanges 12 on the side sills. When the doors D are in open position they direct the discharge of 30 material outside of the rails. Portions of the side sills over the trucks will include integral hinge butts 13 for mounting doors C which swing inwardly against the outer edges of the floor sections 10.

35 Both sets of doors are locked in position to prevent discharge of material in car by well known locking means indicated at E and F and this means forms no part of the present invention. Chains G are provided at each side of the doors 40 D to support the outer portions of the doors when the material is being discharged. The upper portions of the chains are secured to the lugs 19 and 20 formed integral with cross beams 7, and the lower ends are secured to outwardly projecting lugs 21 at the sides of the doors D.

50 The floor extends across the center of the car and substantially from end to end of the car, adjacent sections being interconnected through the transverse members. The intermediate portion of the floor forms a cover plate or top member of the center sill structure and the outer portions of the floor sections form deep reinforcing webs for the center sills. The outer portions of the 55 floor are connected to the side sills by the lower portions of the transverse members and this structure constitutes substantial bracing between the center and side sills.

55 Preferably the bolsters include integral center plate and side bearing elements 14 and 15 respectively, the center plate being reinforced by suitable radial ribs 16. The transverse members 7 have a series of ribs 17 extending between the center sill webs 1 and the under-side of floor sections 9 and 10 and bracing these members across the 65 center line of the car.

70 It is not essential that all of the features described be included in the underframe in order to form a novel structure and many of the features are novel irrespective of the integral cast metal structure preferred. Obviously, the parts may be varied in extent and shape without departing from the spirit of the invention and I contemplate the exclusive use of all modifications coming within the scope of my claims.

75 What is claimed is:

1. In a railway car underframe, a center sill element, and a floor inclined downwardly and outwardly from said element, the outer edge of the portion of said floor over the car trucks terminating substantially beneath the side of the 5 underframe, and the outer edge of the portion of said floor between the car trucks terminating intermediate the side of the underframe and said element.

2. A structure as set forth in claim 1 which 10 includes a side sill and means for mounting hinged doors on said side sill over the car trucks and means for mounting hinged doors on the edge of said floor between the car trucks.

3. In a railway car underframe, transverse 15 members, an inclined floor extending between said members and downwardly and outwardly from the longitudinal center line of the car, the degree of inclination and the width of that portion of the floor over the car trucks being different from that portion of the floor intermediate the car trucks, said portions and members being united and forming a continuous floor surface.

4. In a railway car underframe, a center sill, side sills, a continuous floor inclined downwardly 25 and outwardly from opposite sides of said center sill, and elements connecting said side sills and the lower outer portions of said floor whereby said floor forms a transverse brace between said side sills.

30 5. In a railway car underframe, a center sill, a side sill, a floor extending downwardly and outwardly from said center sill, a transverse member between said sills comprising an upright web with its lower outer portion terminating in diverging flanges extending between said side sill and the lower outer portion of said floor.

6. In a railway car underframe, a center sill, a side sill, and an inclined floor extending downwardly and outwardly from said center sill to 40 wards said side sill substantially throughout the length of the car, the portions of said floor over the car trucks being arranged less steep than the portions of said floor intermediate the car trucks, the portions of said side sill over the car trucks 45 being at a higher level than the portions of said side sill between the car trucks.

7. In a railway car underframe, a center sill, side sills, a transverse transom member between 50 said side sills, and a floor web inclined downwardly and outwardly from opposite sides of said center sill and extending continuously substantially from end to end of the underframe and constructed integrally with said center sill and transverse member.

55 8. In a dump car, a series of hoppers on each side of said car having inclined floor members extending downwardly and outwardly from the transverse center of said car and having discharging openings for discharging material to the sides of the car, the angle of inclination of the inclined floor members for the hoppers over the trucks being less steep than the angle of inclination for the inclined floor members between the trucks, doors forming closures for said hoppers, 60 the doors for the hoppers located over the truck being swingingly mounted at the upper portion of the hoppers, said doors extending downwardly and inwardly, and doors for the hoppers between the trucks swingingly mounted to the outer edges 65 of said inclined floors, said latter doors extending upwardly and outwardly in closed position.

70 9. In a railway car underframe, a center sill, a floor extending downwardly and outwardly from said center sill, and a transverse member extend- 75

ing outwardly from said sill and floor and comprising an upright web with its lower outer portion terminating in diverging flanges merging with the lower outer portion of said floor.

5 10. A railway car underframe comprising in a single casting spaced bolsters, intermediate cross beams, center sill structure, and a floor inclined downwardly and outwardly on both sides of the longitudinal center line of the car and merging 10 with said bolsters, cross beams, and center sill structure.

10 11. In a railway car underframe, an inclined floor extending outwardly and downwardly from the longitudinal center line of the underframe, the degree of inclination and width of that portion 15 of the floor over the car trucks being differ-

ent from that portion of the floor intermediate the car trucks, said portions being united to form a substantially continuous floor surface from end to end of the car.

12. In a railway car underframe, an inclined floor extending downwardly and outwardly in opposite directions from the longitudinal center line of the underframe, the degree of inclination and the width of those portions of the floor over the car trucks being different from those portions 10 of the floor intermediate the car trucks, all of said portions being united to form a substantially continuous floor surface from end to end of the car.

JOHN E. MUHLFELD. 15
